UNITED STATES PATENT OFFICE.

JACOB R. SANDAGE, OF CHICAGO, ILLINOIS, ASSIGNOR OF ONE-HALF TO WARREN R. SANDAGE, OF CHICAGO, ILLINOIS.

HEATING FURNACE.

Application filed March 9, 1925. Serial No. 13,946.

This invention relates to furnaces for heating houses and buildings, and more particularly to those which employ some means for heating air for this purpose, and for circulating the air through the furnace and into the rooms to be heated.

Generally stated, the object of the invention is to provide a novel and improved construction whereby the air will be brought into the furnace and taken across the same, close to the fire, directly above the fire pot of the furnace, so that the air will be more intensely heated, and whereby a smaller fire will be more effective in heating the air, and whereby even an oil burner or a gas burner, when placed in the fire pot, will be more efficient for the heating of the air than is possible with the ordinary construction of coal-burning hot air furnace.

It is also an object to provide certain details and features of construction and combinations tending to increase the general efficiency and desirability of a heating furnace of this particular construction.

To these and other useful ends, the invention consists in the matters hereinafter set forth and claimed, and shown in the accompanying drawings, in which:

Fig. 1 is a vertical section of a hot air heating furnace embodying the principles of the invention;

Fig. 2 is a horizontal section on line 2—2 in Fig. 1;

Fig. 3 is a horizontal section on line 3—3 in Fig. 1.

As thus illustrated, the invention comprises an outer furnace casing 1 of any suitable or desired form or character, together with a fire pot 2, of any suitable or desired character therein. An upper door 3 is provided for the introduction of the fuel into the fire pot, and the lower door 4 is provided for the withdrawal of the ashes which are dumped into the ash pit below. A smoke pipe 5 is provided, as shown, leading from the upper portion of the casing of the furnace, thereby to provide an outlet for the smoke and products of combustion.

A heating drum 6 is provided in the upper portion of the casing, as shown, with space 7 between the sides of the drum and the casing of the furnace. This drum has its upper portion enlarged and provided with one or more outlets 8 for the escape of the heated air. The lower portion of the drum is pro-

vided with a horizontal baffle 9, and with an air inlet space 10 immediately below this baffle. The lower portion of the furnace casing is provided with a cold air inlet 11, and just above this inlet with a baffle 12, so that the cold air enters as shown and circulates around the fire pot 2, and around the lower portion of the wall 13 of the furnace casing before being drawn into the space 10, and from the latter into the heating drum 6, previously mentioned. Thus, the air is first heated by circulation around the fire pot, and is then heated in the drum 6, and it will be observed that when the air enters the drum, it does so directly over the fire and directly over the bottom wall 14 of the heating drum, where the heat is most intense, raising the air to a high temperature in the bottom portion of the drum. The smoke and products of combustion pass upwardly in the space 7, thus heating the sides of the drum 6, so that the interior of the lower portion of the drum is subjected at all sides thereof, and below, to the full force of the heated gases rising from the fire.

With this arrangement, therefore, a smaller fire can be employed, and, if desired, an oil burner or a gas burner may be used effectively in the fire pot. In other words, the air is given a preliminary heating around the outside of the fire pot, and is then intensely heated when it enters the lower portion of the heating drum, directly over the fire, and with an arrangement of this kind, involving the bringing of the air very close to the fire, it is obvious that the air can be effectively heated with less fuel than would be required with some other constructions.

It will also be observed that the air is taken into the heating drum 6 in a manner to keep the bottom thereof from burning out, inasmuch as the air, although it is heated by circulation around the fire pot, is at a relatively low temperature when it enters the bottom of the drum, and the baffle 9 keeps the air that has just entered down against the bottom of the drum in a manner to prevent the bottom wall of the drum from burning out. Of course, this bottom wall of the drum can be made of any suitable known or approved material, and can be made of some special material which will not be liable to burn out even though the air were not being circulated throughout the furnace.

It will be understood, of course, that the drum 6 is gas-tight, so that no gases or products of combustion rising with the fire can enter and mingle with the air. The bottom 5 wall 14 of the drum is imperforate, and hence the space 7 constitutes the only passage for the smoke and products of combustion upwardly to the smoke pipe 5 through which the smoke is allowed to escape from 10 the furnace.

It will be seen that the drum 6 is concentric to the top of the fire pot, so that an annular space is formed between the drum and upper edge of the fire pot. The plate 13 15 closes the rear portion of the space between the drum and the fire pot, to form an intake directly over the upper edge of the fire pot into the drum, and a similar plate 14 is disposed directly over the plate 13, so that 20 these plates form the top and bottom walls of the lateral intake of the drum. This leaves the front portion of the space between the lower edge of the drum and the upper edge of the fire pot open, for the upward 25 passage of the smoke and gases, and the latter then pass over the plate 14 into the smoke pipe, which latter is directly above the said intake of the drum. Thus the air enters the drum and spreads out upon the 30 flat back wall thereof, so as to receive the maximum heat from the fire upon entrance into the drum, and the baffle 9, which is in the plane of the top plate 14 of the intake, tends to keep the incoming air down upon 35 the bottom wall of the drum to not only heat the air effectively, but also to keep the said bottom wall 14 from becoming overheated and burning out, the air entering and absorbing the heat so promptly that the temper- 40 ature of the bottom wall is much less liable to burn out than might otherwise be the case if it were not constantly giving up its heat to the incoming air.

Without disclaiming anything, and without prejudice to any novelty disclosed, what 45 I claim as my invention is:

1. In a heating furnace for heating air, the combination of a furnace casing and a fire pot therein, an air heating drum suspended in the upper portion of the furnace casing, with its bottom wall concentric to the top of said fire pot, for heating all the air passing through the furnace, and of less 50 diameter than the top of the fire pot, and disposed in position directly over the fire pot, said drum having an intake directly over the rear edge of the fire pot for admitting air laterally through the side of the lower portion of the heating drum, so that 55 the air enters and spreads directly over and upon said bottom wall, whereby all air taken in and heated by the furnace must pass 60

through said drum, with space around the outside of the drum for the passage of smoke and the products of combustion, a smoke pipe leading from the upper portion of said space around the outside of the heating drum, whereby the bottom and sides of said drum are heated, and an outlet for the upper portion of said drum, forming a hot air off-take for the furnace, whereby only air passing through said drum can escape through said off-take, said intake closing a portion of the annular space between the drum and the upper edge of the fire pot, leaving the front portion of said space unobstructed to permit upward escape of the products of combustion from the fire pot, and a top wall for said intake over said closed portion of said space, over which top plate the products of combustion pass to said smoke pipe. 65 70 75 80

2. A structure as specified in claim 1, in combination with a horizontally disposed baffle in said drum, in the plane of said top wall, immediately above the lateral air intake thereof, whereby the air enters and flows across the bottom wall of the drum, and then rises between the farther side of the drum and the edge of said baffle. 85

3. A structure as specified in claim 1, in combination with means for the passage of air around the outside of said fire pot, before the passage of air into the drum through the said intake thereof, thereby to preliminarily heat all of the air passing through the furnace, before it enters said drum. 90 95

4. A structure as specified in claim 1, comprising instrumentalities for admitting the air and first circulating it around the fire pot, before the air passes into said drum, 100 thereby to preliminarily heat all of the air passing through the furnace, said instrumentalities including a horizontally disposed baffle extending partially around the fire pot, below said intake of the drum, 105 whereby the air is caused to enter at one side of the base portion of the furnace casing, below said intake of the drum, and then travel across to the other side, at each side of the fire pot, and then upwardly between the ends of the baffle and the farther side of the furnace casing before entering said drum. 110

5. A structure as specified in claim 1, the bottom of said drum being flat and imperforate, and said space around the outside of the drum constituting the only passage for the smoke and products of combustion upwardly to the smoke pipe, there being an air heating chamber overhanging the top of said smoke space, forming an enlarged head for 115 120 said drum.

Specification signed this 2nd day of March, 1925.

JACOB R. SANDAGE.
